UNITED STATES PATENT OFFICE.

ROBERT ROSS KAYLOR, OF FRANKLIN, PENNSYLVANIA.

DESIGN FOR A PICKER-TOOTH.

SPECIFICATION forming part of Design No. 33,819, dated January 1, 1901.

Application filed December 3, 1900. Serial No. 38,576. Term of patent 14 years.

To all whom it may concern:

Be it known that I, ROBERT ROSS KAYLOR, a citizen of the United States, residing at Franklin, in the county of Venango and State of Pennsylvania, have invented and produced a new and original Design for a Picker-Tooth; and I do hereby declare the following to be a full, clear, and exact description of the invention, such as will enable others skilled in the art to which it appertains to make and use the same.

My invention relates to a new and original design for a picker-tooth to be used in connection with machines for picking, separating, and threshing fibrous materials and grain; and the design consists of the essential characteristics substantially shown in the accompanying drawings and hereinafter more specifically described.

In the accompanying drawings, which illustrate my design, Figure 1 is a side elevation of my picker-tooth. Fig. 2 is an end view looking to the left in Fig. 1.

The leading feature of my design consists in the peculiar shape of the picker-tooth, which has an enlarged approximately central portion of the general contour of a pair of inverted cones placed base to base.

1 designates the line of greatest circumference and is approximately the central portion of my picker-tooth, from which point it tapers gradually toward one end, as represented at 2, and tapers in the opposite direction, as shown at 3, for a short distance, when it assumes the form of the cylindrical portion 4, screw-threaded, as designated at 5, the whole effect presenting to the eye the design, shape, and configuration of a pair of oppositely-disposed truncated cones placed base to base, one of which cones terminates in a cylindrical portion provided with a screw-threaded end.

What I claim is—

The design for a picker-tooth for use in connection with machines for picking, separating and threshing fibrous materials and grain or for similar purposes, substantially as herein shown and described.

In testimony whereof I affix my signature in presence of two witnesses.

ROBERT ROSS KAYLOR.
